CUSHION COVERING FOR MOP HANDLES

Filed Feb. 16, 1928

UNITED STATES PATENT OFFICE.

LORETTA STOESSEL, OF OTTUMWA, IOWA.

CUSHION COVERING FOR MOP HANDLES.

Application filed February 16, 1928. Serial No. 254,735.

This invention relates to new and useful improvements in coverings for mop handles and aims to provide a novel, simple and inexpensive cushion covering, for arrangement 5 around the handle of a mop, and directly adjacent the head of a mop, so as to protect chairs, tables and other articles of furniture from becoming marred by being struck by the handle when the mop is pushed beneath 10 said furniture.

One of the most important objects of this invention is to provide a cushion covering of this character that may be readily applied to the handle and when once applied 15 may be considered a permanent part of the mop and that will furthermore not interfere with the proper use of the mop.

Furthermore, the cost of a covering of this character is so negligible that a number of 20 the same may be on hand for renewing the covering as the same wears out.

In the drawing, wherein like reference characters indicate corresponding parts throughout both of the views:

25 Figure 1 is a perspective of a generally conventional mop, the handle thereof being equipped, adjacent the mop head with one of my improved cushion covers, and

Figure 2 is a view mainly in side elevation and partly in cross section of the cover per se.

Now having particular reference to the drawing, there is disclosed in Figure 1 a generally conventional mop consisting of a 35 head A, and a handle B, which handle is usually pivoted to the rear end of the mop head as generally suggested by the dotted lines in said figure. My cushion cover consists of an elongated sleeve 5 of rubber or 40 other suitable material, of a cross sectional shape, similar to the cross sectional shape of the handle B and adapted to be snugly arranged upon the handle adjacent the mop head A. The length of this cover should be 45 such as to engage over a substantial area of

the handle B, adjacent the mop head A, so that when the mop head is moved beneath chairs, tables, or other articles of furniture, the bare handle will not contact the furniture and thus mar the same. However, I do not 50 desire to be limited to any particular length of this cover.

The lower end of the sleeve 5 merges into a sphere 6, the foremost surface thereof being cut away to provide a substantially 55 semi-circular slot 7, whereby the forward ends of this sphere may be arranged over the front and back sides of the pivot connection between the head A and handle B, as is also disclosed in Figure 1, so that the 60 said pivotal connection will also be equipped with a cushion cover.

It will thus be seen that I have provided a highly novel, simple and extremely useful 65 cushion cover for mop handles that is well adapted for all of the purposes heretofore designated, and even though I have herein shown and described the invention as consisting of a certain structure, it is nevertheless to be understood that minor changes 70 may be made therein without affecting the spirit and scope of the appended claims.

Having thus described my invention what I claim as new is:

1. A protective cover for mops comprising a sleeve adapted to fit over the handle of a mop, and an extension at the lower end of said sleeve adapted to engage over the head portion of the mop to protect furniture against which the mop may come in contact. 75

2. A protective cover for mops comprising an elongated sleeve of cushion material adapted to be arranged over the handle of a mop, and a pair of enlarged flaps at the lower end of said sleeve adapted to engage 80 opposite sides of the mop head to protect furniture against which the mop may come in contact. 85

In testimony whereof I affix my signature.
LORETTA STOESSEL.
